UNITED STATES PATENT OFFICE

133,970

DESIGN FOR A MILLING MACHINE

Robert S. Condon, Rutland, Vt.

Application August 4, 1942, Serial No. 107,813

Term of patent 14 years

To all whom it may concern:

Be it known that I, Robert S. Condon, a citizen of the United States, residing at Rutland, county of Rutland, State of Vermont, have invented a new, original, and ornamental Design for a Milling Machine, of which the following is a specification, reference being had to the accompanying drawing, forming a part thereof.

In the drawing:

Fig. 1 is a front elevational view of a milling machine showing my new design.

Fig. 2 is an elevational view of one side thereof.
Fig. 3 is an elevational view of the other side thereof.

Fig. 4 is a rear elevational view thereof.

I claim:

The ornamental design for a milling machine, substantially as shown.

ROBERT S. CONDON,
